CLAIM

The ornamental design for a hanger, as shown and described.

DESCRIPTION

FIG. 1 is a perspective view of a first embodiment of a hanger according to the disclosed design;
FIG. 2 is a front view of the hanger shown in FIG. 1;
FIG. 3 is a rear view of the hanger shown in FIG. 1;
FIG. 4 is a first side view of the hanger shown in FIG. 1;
FIG. 5 is a second side view of the hanger shown in FIG. 1;
FIG. 6 is a top view of the hanger shown in FIG. 1;
FIG. 7 is a bottom view of the hanger shown in FIG. 1;
FIG. 8 is a perspective view of a second embodiment of a hanger according to the disclosed design;
FIG. 9 is a front view of the hanger shown in FIG. 8;
FIG. 10 is a rear view of the hanger shown in FIG. 8;
FIG. 11 is a first side view of the hanger shown in FIG. 8;
FIG. 12 is a second side view of the hanger shown in FIG. 8;
FIG. 13 is a top view of the hanger shown in FIG. 8; and,
FIG. 14 is a bottom view of the hanger shown in FIG. 8.
The broken line showing of visible environmental structures is for illustrative purposes only and forms no part of the claimed design.
